REFUSE BAG HOLDER

Richard T. Kane, Rochester, N.Y., assignor to Mobil Oil Corporation

Filed Mar. 23, 1972, Ser. No. 237,599

Term of patent 14 years

Int. Cl. D7—07

U.S. Cl. D7—193

FIG. 1

FIG. 2

FIG. 4

FIG. 1 is a perspective view of the refuse bag holder, with a portion of the base broken away in order to show the exact configuration of the base.

FIG. 2 is a plan view thereof.

FIG. 3 is a side view thereof.

FIG. 4 is a bottom view thereof.

I claim:

The ornamental design for a refuse bag holder, as shown and described.
